(57) **CLAIM**

The ornamental design for a power connector, substantially as shown and described.

DESCRIPTION

FIG. 1 is a perspective, top view of the power connector showing our new design;

FIG. 2 is a left side view thereof, the right side a mirror image thereof;

FIG. 3 is a top side view thereof, the bottom side a mirror image thereof;

FIG. 4 is a front view thereof; and,

FIG. 5 is a back view thereof.

The broken lines in the Figures are for illustrative purposes only and form no part of the claimed design.
